UNITED STATES PATENT OFFICE.

THOMAS ALLATT, OF WESTFIELD, NEW JERSEY.

ADVERTISING DEVICE.

Application filed December 29, 1923. Serial No. 683,336.

To all whom it may concern:

Be it known that I, THOMAS ALLATT, a subject of Great Britain, residing at Westfield, in the county of Union, State of New Jersey, have invented certain new and useful Improvements in Advertising Devices; and I do hereby declare the following to be a full, clear, and exact description of the invention, such as will enable others skilled in the art to which it appertains to make and use the same.

This invention relates to advertising devices and has to do more particularly with a device of the type generally referred to as a moving sign.

Such devices ordinarily consist of a casting having a display aperture, and across this aperture is moved a strip or tape on which the advertisement appears. In one form of device the tape used is endless and the driving mechanism is so arranged that the tape continually moves in one direction across the opening. The slack of the tape is supported by suitable guides which direct it in a tortuous path.

In another form of machine the tape is carried on a pair of spools or cores and is wound from one to the other. In this form of apparatus an automatic reversing mechanism is provided so that when the tape has been entirely wound on one spool the driving devices are reversed and the tape is rewound upon the first spool.

In devices of the type just referred to the tape which carries the advertisement passes across the display opening in a horizontal direction and the advertising matter is conveniently read only when the tape is moving from right to left, since this gives the same effect as if the observer were to pass his eye across a stationary tape in the reverse direction. In this form of mechanism when the tape has all been transferred from one spool to the other and has passed in this movement across the aperture from right to left, it follows that the words appearing on the tape cannot be easily read in the reverse movement of the tape. If the advertisement is to be of considerable length or is to be repeated many times, it is necessary to employ a tape of great length and this requires that the spools on which the tape is to be wound should have an excessive storage capacity. This form of mechanism, however, is on the whole considerably simpler

than one in which an endless tape is used since, as has previously been described, provision must be made for the slack of the tape and consequently when a new tape is to be placed in the machine so as to present new advertising matter, the threading of the tape through the various guides which are necessary is quite complicated and difficult.

The use of a mechanism employing a tape which is wound from one spool to the other and then automatically rewound is much simpler in construction and it is much easier to change the tape whenever occasion demands. This form of device, however, has the objectionable feature above pointed out; that is, during the rewinding of the tape the message cannot easily be read.

The present invention is intended to provide an advertising device having a tape wound and rewound on a pair of spools which overcomes the objectionable feature above referred to, and which permits of the exposure of a portion of the tape which is always moving in the direction for easy reading, regardless of which spool the tape is being wound upon. In the machine of the present invention the tape passes across the aperture from one spool to the other in two stretches which move in opposite directions. In one stretch the front face of the tape is exposed, while in the other the rear face is visible. There is also provided a curtain which may be used to conceal one stretch or the other. When the mechanism is in operation that stretch is exposed which is moving from right to left, and which, therefore, may be easily read. When the reversing operation occurs the curtain also moves so as to conceal the opposite stretch and in this way during both the first winding and the reversal there is exposed a moving tape which passes in the direction across the aperture from right to left. In this machine, since both the front and rear portions of the tape are alternately exposed, it is possible to use a tape which carries advertising matter on both faces and consequently an advertisement of double length may be carried on the tape. In this machine a new tape may be mounted in place with great convenience and when once the machine is started the operation of the several parts is automatic and requires no attention.

The principles of the invention may be

utilized in many different forms of apparatus, but in the accompanying drawings there is illustrated one form of device embodying the invention. In these drawings,

5 Fig. 1 is a face view of the device showing the aperture and the tape,

Fig. 2 is a top plan view of the device with the cover removed,

10 Fig. 3 is a sectional view on the line 3—3 of Fig. 2,

Fig. 4 is another sectional view on the line 4—4 of Fig. 2,

15 Figs. 5 and 6 are details of the tape and the means by which the tape is secured to one of the spools respectively.

20 In these drawings the device is seen to consist of a housing 7 having a removable cover 8. In the front wall of this housing is an aperture 9 of any convenient size, but here shown of a size sufficient to expose two stretches of the tape, lying side by side. This housing is preferably closed by a pane of glass.

25 Mounted in any convenient location in the housing is a driving motor 10, carrying a pulley 11, over which runs a belt 12. A supporting frame 13 is mounted in the housing and extends upwardly from the bottom thereof. In this support is carried, in suitable bearings, a horizontal shaft 14, carrying a grooved pulley 15 in which the belt travels. On the other end of this shaft is a beveled gear 16 and mounted vertically in the frame is a shaft 17. This shaft rests at 30 its lower end against a circular plate 18. Loosely mounted on the shaft near the upper end thereof below the top bar of the frame, is a compound gear 19 consisting of a beveled gear 20 meshing with the beveled gear 16, and a spur gear 21. Secured to the shaft 17 below the gear 21 is a bracket 22 having a pair of lateral arms 23 and 24. This bracket is rigidly secured to the shaft 17 and through the ends of the arms is 35 loosely mounted an auxiliary shaft 25 carrying a pair of collars 26 which serve to hold it in place in the bracket. The shaft 25 carries at its upper end above the upper arm 23, a spur gear 27 meshing with the similar gear 21 which forms a portion of 40 the compound gear. At its lower end the shaft 25 carries a roller 28 which is preferably composed of some resilient material such as soft rubber. The circular plate 18 has an upstanding flange 29 at its periphery and the parts are proportioned so that under certain conditions, which will later be described, the roller 28 will contact with the inner face of this flange and as the shaft 25 is driven the roller will be caused 45 to traverse the flange and thus cause the auxiliary shaft and the bracket to rotate about the axis of the shaft 17.

50 Secured to the base on either side of the disc 18 are hollow spindles 30, 31. The

lower end of the spindle 30 rests on a plate 32 secured in the base, and extending upwardly through this plate is a rod 33 carrying a collar 34 at its upper end which serves to keep the rod spaced from the inner surface of the spindle. At its lower end the spindle rests on a shoulder 35 formed on the plate 32. Formed integrally with the spindle is a flanged disc 36. The spindle 31 is of similar construction, resting on a shoulder 37 on a plate 38 from which extends upwardly a rod 39 carrying a collar 40 at its upper end. This spindle also has formed integrally with it a flanged disc 41, corresponding to the disc 36. The upper surface of the disc 36 is mounted to support a core 42 upon which the tape is to be wound, as will presently be described. This core has a bore 43 extending upwardly from its lower surface in which is to be received a pin 44 mounted in the disc, the pin serving to prevent the core from rotating relative to the disc. The spindle 31 carries a collar 45 which serves as a support for a disc 46 on which a core 47 is mounted, the disc having a pin 48 which extends into a bore in this core.

55 The flanged discs 36 and 41 extend toward the plate 18 and the flange of the latter, as is shown in Fig. 2, is cut away at 49 and 50 so that at these points the peripheries of the discs will lie flush with the inner face of the flange 29 and thus be engaged by the roller 28 as the latter traverses this flange. Mounted on the flange, near the points at 60 which the latter is cut away, are stops 51 and 52. These stops have portions 53 and 54 which extend inwardly beyond the face of the flange. The stops are in the form of levers pivoted at 55 and 56 respectively and have projections 57 and 58 to which are secured the ends of coiled springs 59 and 60, the other ends being secured to portions of the frame 13 at 61 and 62. The stop 52 has pivoted to it a lever 63 by 65 which it may be rocked in the manner presently to be described, and a similar lever 64 is rigidly connected to a portion of the stop 51. For this purpose the stop may have a pin received in an aperture in the end of the arm 64, the latter having a set screw 64' bearing against the pin so that the stop and arm 64 are secured together and movable as one. The bracket 22 carries an arm 65 which is of sufficient length to engage the projecting portions 53 and 54 of the two stops and whenever this arm 65 lies against one stop or the other the roller 28 will be held opposite one of the cut-out portions of the flange 29 and will accordingly make 70 contact with one or the other of the discs 36 and 41, thus causing the spindle associated with that disc to be rotated.

75 The spindles have been described as providing supports for cores 42 and 47. The

core 47 normally carries a tape 66 which is led from the core 47 over a roller 67 mounted in any convenient manner on the frame 13. From the roller 67 the tape passes to 5 the upper one of a pair of rollers 68 and 69 mounted loosely on a shaft 70 in the forward part of the casing at one end of the aperture 9. These rollers are separated by a spacing disc 71. From this roller the tape 10 passes across the front of the aperture to the upper of a similar pair of rollers indicated at 72. Thence the tape passes rearwardly over a roller 73 mounted in a bracket 74 secured to the bottom of the casing, thence 15 rearwardly over an inclined guide 75. This guide is mounted on a shaft 76 secured in a bracket 77 fastened to the base, and the shaft extends at an angle of approximately 45° upwardly from the base. The guide 75 20 is seen to have side flanges between which the tape passes, and, coming from the guide 75, the tape passes forwardly to the bottom roller of the pair mounted at 72, thence across the aperture to the roller 69, thence 25 rearwardly to the core 42. It will be seen that the tape, in passing from one spool to the other, travels across the aperture in two stretches. When the tape is being wound off the spool 47 upon the spool 42, the upper 30 stretch is moving from left to right and the lower stretch from right to left. It will also be seen that in passing from the upper stretch to the lower stretch around the guide 75 the exposed face of the tape is reversed; 35 that is, that face which lies to the front of the aperture in the upper stretch will have been turned toward the rear in the lower stretch.

The mechanism by which the tape movement is reversed when all the tape has been 40 wound on one spool is as follows: An arm 78, having a pair of pins located close together at its outer end is pivotally mounted at 80 in a suitable bracket secured to the base. 45 The tape passes between these pins in traveling from the core 47 to the upper guide roll 68. Pivotally mounted near the rear end of this arm is an arm 81 which is pivotally connected at its other end to the arm 64 and the 50 connections are such that when the arm 78 is swung about its pivot in the direction in which the tape is moving, as indicated by the arrow in Fig. 2, the stop 51 will be caused to rock on its pivot and thus permit the arm 65 to clear its end 53. Near the other end of the tape just before it passes onto the core 42 is an arm 82 also carrying a pair of pins 55 placed close together and through which the tape passes. This arm is pivotally mounted at 84 on a suitable support on the base and pivoted near its rear end is the arm 63 which is secured to the end of the stop 52. 60

When the device is to be started the tape 65 is led off through the various guides and in

the path described, finally passing to the core 42 where the end of it is connected to a strap 85, one end of which is secured to the core. This strap carries a bar 86, shown more clearly in Fig. 6, and the bar is of 70 such size that it cannot pass between the pins 83. The core is channeled as at 87 so as to form a recess in which the bar will lie when the tape is wound on the core. The other end of the tape, as is shown in Fig. 5, carries a bar 88, permanently secured to it and the core 47 is channeled as at 89 to form a recess in which this bar will normally lie when the tape is wound up. When the device is being operated, as the tape winds up 75 on the core 42, eventually that portion of the tape carrying the bar 88 will pass off the core 47 around the guide 67 and the bar 88 will come in contact with the pins 79. This will cause the arm 78 to be rocked on 80 its pivot 80, swinging the arm 81, arm 64 and stop 51, and thus causing the end of the stop to clear the end of the arm 65. In the return movement of the tape the bar 86 striking the pins 83 causes a similar swing- 85 90 95 90 95 100 105 110 115 120 125 130

The driving mechanism has previously been described and under normal circumstances the shaft 14 which is continuously 95 driven by the motor 10 will cause a rotation of the compound gear 19, this movement being transmitted through the gears 20 and 27 to the shaft 25 and the roller 28. When the roller is held in position opposite 100 one of the cut-out portions 49 or 50 of the flange 29 the roller will contact with one or the other of the discs 36 or 41, thus causing that disc to be driven and the tape to be wound on the core associated with it. In 105 Fig. 2 the roller is shown driving the disc 36 and thus the tape is being wound on the core 42 off the core 47. The arm 65 is held against movement against the stop 51, and since the compound gear 19 is loose on 110 the shaft 17 there is no tendency for the shaft to rotate. However, when the end of the tape has been reached the bar 88 will strike the pins on the arm 78 and cause the stop 51 to be moved out of the path of the arm 65. The roller 28 will now ride off the exposed portion of the flange 36 and onto the inner face of the flange 29. In this movement the roller not only engages 115 but traverses the flange 29 and thus causes the bracket 25 to revolve about the axis of the shaft 17. The latter shaft on which the bracket is fast, is also caused to revolve and this movement continues until the arm 65 strikes against the portion 54 of the other 120 stop 52, at which time the roller 28 will lie opposite the cut-away portion 50 of the flange 29, and will thus contact with and drive the disc 41. When the disc 41 is 125 driven the core 47 commences to revolve 130

and wind the tape upon it. The reversal of the tape movement is now complete and the tape continues to be wound off the core 42 on the core 47 until another reversal 5 takes place, in the manner previously described, by the bar 86 swinging the arm 82.

It has previously been explained that the tape moves across the aperture in two oppositely moving stretches and in Fig. 1 the 10 lower stretch is illustrated as moving from right to left, the upper stretch, which is concealed, moving from left to right. This concealment is brought about by means of a curtain 90 which is carried on the ends 15 of a pair of straps 91 and 92, the ends of which are secured to a pair of upstanding levers 93 and 94. In Fig. 1 of the drawings a portion of the curtain has been broken away to show the stretch of tape 20 beneath it. These levers are secured in a rod 95 loosely mounted in brackets in the bottom of the casing. An actuating lever 96 extends upwardly from this rod and to the upper end of the lever is secured a pitman 97, the rear end of which is secured to a crank 98 mounted on the upper end of the shaft 17 above the frame 13. It will be recalled that the shaft 17 is normally stationary, except when the roller 28 is traversing the inner face of the flange 29, under 30 which conditions the shaft is caused to rotate by reason of the movement of the bracket 22. When the shaft 17 is so rotating the crank is brought into action and this causes the bar 95 to be rocked in its 35 brackets. This, in turn, causes the arms 93 and 94 to be swung toward or away from the front wall of the casing and so take in or let out the straps 91 and 92 which extend 40 forwardly and pass over guides 99, thus moving the curtain 90 upwardly or downwardly within the aperture. The parts are so constructed that the curtain will always be in position to cover that stretch of the 45 tape which is moving from left to right and which, therefore, cannot be easily read. In Fig. 1 the curtain is covering the upper stretch but when the tape movement is reversed so that this upper stretch is moving 50 from right to left and the lower in the opposite direction the curtain will be dropped down so as to conceal the lower stretch.

When the device is to be set up a tape having the desired advertisement printed on 55 it and carried on a core similar to the core 47 will be mounted in place on the spindle 31. The end of the tape will then be threaded through the various guides, and, passing in a double stretch across the aperture 9, 60 will be led to the core 42 where it will be secured to the strap 85, the other end of which is permanently fastened to the core. For convenience in threading the tape across the 65 various guides there are provided doors 100 which conceal apertures 101 located in

the side walls of the housing near the front in such location that the guides 68, 69 and 72 may be easily reached. The driving mechanism will then be set by hand to bring the roller 28 against the disc 36. Then the 70 motor will be started and this disc driven to wind the tape upon the core of the spool 42. The tape continues to wind off one spool upon the other until eventually the block 88 will engage the pins 79 on the arm 75 78 and cause this arm to swing thus momentarily rendering the stop 51 inoperative. The roller will move out of engagement with the surface of the disc, and moving in a clock-wise direction, as illustrated 80 in Fig. 2, will eventually come into contact with the disc 41 where it is held by the engagement of the arm 65 with the other stop 52. The disc 41 is now driven and the direction of the tape is accordingly reversed 85 and it is now wound off the spool 42 onto the spool 47. This movement continues until the end of the tape is reached, when the reversing mechanism again operates and the tape starts to move in its original direction. The winding of the tape from one spool to the other will continue as long as the motor is driven. With each reversal of the tape 90 the curtain will be brought into action to conceal the stretch which is moving in such direction that the characters on it cannot easily be read; that is, from left to right, and since in these two stretches opposite faces of the tape are placed toward the opening in the housing it is clear that it is possible to use a tape both faces of which 95 carry advertising matter. Thus a tape suitable for use in this machine will carry twice as much advertising matter as could be carried by a tape used in the ordinary 100 machine in which the mechanism is similarly reversed when the end of the tape has been reached. Also in thus exposing both faces of the tape that portion of the sign which may be observed is always moved in 105 the direction which permits the matter to be easily read. When the advertisement is to be changed, the tape is all wound on the spool 47 which is then slipped off its spindle, and a spool carrying a tape having a 110 different advertisement is substituted for it and led through the various guides and connected to the strap on the other spool. These 115 tapes are easily printed and usually a number of them will be prepared for use in a machine and the advertisement or display will be changed from time to time, as may be desired. The mechanism is all self-contained and since it is automatic in action it requires no attention except when the tapes 120 are to be removed and others substituted.

I claim:

1. In an advertising device, the combination of a housing having an aperture, a pair 125 of spools within the housing; a tape connect-

ed to the spools and adapted to be wound off one spool and on the other, this tape having characters on both faces arranged transversely of the length of the tape and forming a message, the words of which follow each other in succession and lie lengthwise of the tape, means for driving the spools alternately, and means for guiding the tape across the aperture in two oppositely moving stretches on which the characters are in upright position and on one of which the words of the message are successively exposed through the aperture in the normal order for reading.

2. In an advertising device, the combination of a housing having an aperture, a pair of spools within the housing, a tape connected to the spools and adapted to be wound off one spool and on the other, this tape having characters on both faces arranged transversely of the length of the tape and forming a message, the words of which follow each other in succession and lie lengthwise of the tape, means for driving the spools alternately, and means for guiding the tape across the aperture in two oppositely moving stretches, in one of which the front face of the tape is exposed, in the other the rear face, the tape being so guided that the characters on it are in upright position and on one of the stretches the words forming the message are successively exposed through the aperture in normal reading order.

3. In an advertising device, the combination of a housing having an aperture, a pair of upright spools within the housing, a tape connected to the spools and adapted to be wound off one spool and on the other, this tape having characters on both faces arranged transversely of the length of the tape and forming a message, the words of which follow each other in a single series and lie lengthwise of the tape, the normal reading order of the words of the messages on opposite faces of the tape being reversed, means for guiding the tape across the aperture in oppositely moving stretches, in one of which the front face of the tape is exposed, in the other the rear face, means for driving the spools alternately and means for concealing the stretch of tape in which the words of the message are successively exposed in an order the reverse of the normal reading order.

4. In an advertising device, the combination of a housing having an aperture, a pair of upright spools within the housing, a tape connected to the spools and adapted to be wound off one spool and on the other, this tape having characters arranged transversely of the length of the tape forming a message, the words of which follow each other in a single series and lie lengthwise of the tape, means for alternately driving the spools with a continuous rotary movement, means for guiding the tape across the aper-

ture in two oppositely moving horizontal stretches, and means for concealing the stretch in which the words of the message are successively exposed in an order the reverse of the normal reading order.

5. In an advertising device, the combination of a housing having a horizontal aperture, a pair of upright spools in the housing, a tape connected at its ends to the spools and adapted to be wound off one and on the other, this tape carrying characters arranged transversely of the length of the tape and forming a message, the words of which follow each other in succession and lie lengthwise of the tape, means for driving the spools alternately, guides for directing the tape lengthwise of the housing in oppositely moving horizontal stretches, a curtain for concealing one of these stretches, and means for automatically reversing the direction of tape movement when a predetermined length has been wound off either spool.

6. In a device of the class described, the combination of a housing having an aperture, a pair of spools within the housing, a tape connected at its ends to the spools and adapted to be wound off one on the other, means for driving the spools, means for guiding the tape across the aperture in oppositely moving stretches, means for concealing one of the stretches, means for automatically reversing the direction of movement and for causing the concealing means to conceal the other stretch upon such reversal.

7. In an advertising device, the combination of a housing having a horizontal aperture, a pair of upright spools within the housing, a tape connected to the spools and adapted to be wound off one spool and on the other, this tape bearing characters transversely disposed on the tape forming a message, the words of which extend in a single series and lie lengthwise of the tape, guides for directing the tape across the aperture in horizontal, oppositely moving stretches, one above the other, and means for alternately driving the spools.

8. In an advertising device, the combination of a housing having an aperture, a pair of spools within the housing, a tape connected at its ends to the spools and adapted to be wound off one spool and on the other, this tape carrying characters arranged transversely of the length of the tape and forming a message, the words of which follow each other in a single series and lie lengthwise of the tape, guides for directing the tape across the aperture in two oppositely moving horizontal stretches, one above the other, a curtain for concealing that stretch of the tape on which the words are successively exposed in an order the reverse of the normal reading order, means for reversing the direction of tape movement when a predetermined length of tape has been wound

- on either spool, and means rendered operative by the reversing means, for moving the curtain to conceal the other stretch of the tape.
5. 9. In a device of the class described, the combination of a housing, a pair of spools within the housing, a tape connected at its ends to the spools and adapted to be wound off one spool on the other, a disc operatively connected with each spool, a driven roller movable to engage either disc, means for holding the driven roller in engagement with one disc or the other to rotate the spool, means for causing the roller to move from one disc to the other to cause a reversal of the direction of the tape movement, and means carried by the tape for actuating said means last mentioned.
10. In a device of the class described, the combination of a housing, a driven shaft therein, said shaft being revoluble about an axis while the connections by which it is driven are maintained, a roller on the shaft, a pair of discs engaged by the roller as the shaft revolves, a spool operatively connected with each disc, a tape connected at its ends to the spools and adapted to be wound off one and upon the other, means for holding the shaft against revolution with the roller engaging one disc, means for permitting the shaft to revolve and bring the roller into engagement with the other disc to reverse the direction of tape movement, and means carried by the tape for bringing said last named means into action.
11. In a device of the class described, the combination of a housing, a driven shaft therein, said shaft being revoluble about an axis while the connections by which it is driven are maintained, a roller on the shaft, a pair of discs engaged by the roller as the shaft revolves, a spool operatively connected with each disc, a tape connected at its ends to the spools and adapted to be wound off one and upon the other, a stop for each spool and operable to hold the shaft against revolution with the roller in contact with that spool, and means for momentarily rendering one stop inoperative to permit the shaft to revolve and bring the roller into contact with the other disc.
12. In a device of the class described, the combination of a housing, a driven shaft therein, said shaft being revoluble about an axis while the connections by which it is driven are maintained, a roller on the shaft, a pair of discs engaged by the roller as the shaft revolves, a spool operatively connected with each disc, a tape connected at its ends to the spools and adapted to be wound off one and upon the other, a stop for each spool and operable to hold the shaft against revolution with the roller in contact with that spool, and means actuated by the tape movement for momentarily rendering one stop in-
- operative to permit the shaft to revolve and bring the roller into contact with the other disc.
13. In a device of the class described, the combination of a housing, a driven shaft within the housing carrying a gear, a second shaft within the housing carrying a loosely mounted gear driven by the first gear, a bracket fast on the second shaft carrying a loosely mounted auxiliary shaft, a gear fast on the auxiliary shaft driven by the loose gear on the second shaft, a roller on the auxiliary shaft, a pair of spindles carrying discs, spools on the spindles, a tape connected at its ends to the spools and adapted to be wound from one to the other, and means for holding the bracket against movement with the roller engaging one of the discs to wind the tape on the spindle carrying said disc.
14. In a device of the class described, the combination of a housing, a driven shaft within the housing carrying a gear, a second shaft within the housing carrying a loosely mounted gear driven by the first gear, a bracket fast on the second shaft carrying a loosely mounted auxiliary shaft, a gear fast on the auxiliary shaft driven by the loose gear on the second shaft, a roller on the auxiliary shaft, a pair of spindles carrying discs, spools on the spindles, a tape connected at its ends to the spools and adapted to be wound from one to the other, a stop for each spindle adapted to hold the bracket against movement with the roller engaging the disc on that spindle, and means actuated by the tape movement for momentarily rendering one of the stops inoperative to permit the roller to move to and engage the other disc.
15. In a device of the class described, the combination of a housing having an aperture, a driven shaft within the housing carrying a gear, a second shaft loosely mounted in a support, a gear loose on the shaft meshing with the first gear, a bracket fast on the second shaft carrying a loosely mounted auxiliary shaft carrying a gear driven by the second gear, a roller on the auxiliary shaft, a circular disc having a flanged edge adapted to be engaged and traversed by said roller to cause a rotation of the second shaft, apertures in the flanged edge of the disc, a pair of spindles having discs extending into said apertures, spools on the spindles, a tape connected at its ends to the spools and adapted to be wound from one to the other, and means for each spindle holding the bracket against movement with the roller engaging the disc through one of the apertures.
16. In a device of the class described, the combination of a housing having an aperture, a driven shaft within the housing carrying a gear, a second shaft loosely mounted

in a support, a gear loose on the shaft meshing with the first gear, a bracket fast on the second shaft carrying a loosely mounted auxiliary shaft carrying a gear driven by the 5 second gear, a roller on the auxiliary shaft, a circular disc having a flanged edge adapted to be engaged and traversed by said roller to cause a rotation of the second shaft, apertures in the flanged edge of the disc, a pair 10 of spindles having discs extending into said apertures, spools on the spindles, a tape connected at its ends to the spools and adapted to be wound from one to the other, guides for directing the tape across the aperture in 15 two stretches, a curtain for concealing one of the stretches, a stop for each spindle adapted to hold the bracket against movement with the roller engaging and driving the disc associated with that stop, means for 20 releasing the stop and permitting the roller to traverse the flanged edge of the circular disc to engage the other disc through the aperture in said edge, and means actuated when the stop is released for moving the 25 curtain.

17. In a device of the class described, the combination of a housing having an aperture, a driven shaft within the housing carrying a gear, a second shaft loosely mounted in a support, a gear loose on the shaft

meshing with the first gear, a bracket fast on the second shaft carrying a loosely mounted auxiliary shaft carrying a gear driven by a second gear, a roller on the auxiliary shaft, a circular disc having a flanged edge adapted to be engaged and traversed by said roller to cause a rotation of the second shaft, apertures in the flanged edge of the disc, a pair of spindles having discs extending into said apertures, spools on the spindles, a tape connected at its ends to the spools and adapted to be wound from one to the other, guides for directing the tape across the aperture in two stretches, a curtain for concealing one of the stretches, a stop for each spindle adapted to hold the bracket against movement with the roller engaging and driving the disc associated with that stop, means actuated by the tape for releasing the stop and permitting the roller to traverse the flanged edge of the circular disc until held by the other stop in engagement with the other disc through the aperture in said flanged edge, and means actuated by the traversing movement of said roller for moving the curtain to conceal the other strip.

In testimony whereof I affix my signature.

THOMAS ALLATT.
